UNITED STATES PATENT OFFICE.

CYPRIEN CHABOT, OF PHILADELPHIA, PENNSYLVANIA.

SOLE-EDGE TURNING OR BENDING MACHINE.

SPECIFICATION forming part of Letters Patent No. 247,305, dated September 20, 1881.

Application filed February 23, 1881. (No model.)

To all whom it may concern:

Be it known that I, CYPRIEN CHABOT, a citizen of the United States, residing in Philadelphia, Pennsylvania, have invented certain 5 Improvements in Sole-Edge Turning or Bending Machines, of which the following is a specification.

My invention relates to certain improvements in that class of machines designed for 10 bending or turning down the edge of a shoe-sole after it has been subjected to the action of the channeling-machine, the main objects of my improvements being to provide for the proper feeding of the sole without interference 15 with the action of the edge-turning wheels, and to insure the opening of the thread-slot which has been formed in the sole by the channeler. These objects I attain in a manner too fully described hereinafter to need 20 detailed preliminary explanation.

In the accompanying drawings, Figure 1 is a longitudinal section of my improved sole-edge-turning machine; Fig. 2, a front view of part 25 of the same; Fig. 3, a view of the edge of the sole as prepared by the channeling-machine; and Fig. 4, a diagram illustrating the character of the work performed by my improved machine.

A represents a post or column having a flaring base adapted to be secured to a table or similar support. On the upper end of this post A is formed a yoke or frame, B, the opposite vertical standards of which are provided with bearings for two longitudinal shafts, 35 D and E, arranged one above the other, the upper shaft, E, having its bearings directly in the frame B, and the lower shaft, D, being adapted to boxes G and H, the former of which is pivoted at x to the rear standard of the 40 frame B, while the box H is at liberty to slide vertically in the front standard of the frame, the depression of the box being effected by means of a rod, R, which extends down through the supporting-table and is connected to a 45 suitable treadle, a coiled spring, S, tending to elevate the box, and the tension of this spring being regulated by means of an adjusting-screw, T, adapted to a threaded opening in the base of the post A.

50 The boxes G and H may be independent of

each other; but it is preferred to connect them together either by a frame, as shown in Fig. 1, or by suitable rods, so that the movement of the boxes may be effected without any strain upon the shaft D.

The front or projecting end of the shaft E is slightly enlarged in diameter and is furnished with a beveled shoulder, g, and the front or projecting end of the shaft D is reduced in diameter for the reception of a beveled ring, j, 6c and has a central opening for the reception of the stem of a block, i, having a rounded or V-shaped edge, the ring j, and block i being firmly secured to the shaft D and acting in conjunction with the flange g on the shaft E, 6: to effect the turning or bending of the edge of the sole.

The ring j and block i may be cast in one piece, if desired; but it is preferable to make them separate, as described, in order that 7c either part can be changed to suit the varying character of the edges of the soles which have to be acted upon.

The shaft E is made tubular for the reception of a spindle, e, which is secured to the said shaft E at the rear end, the front end of the spindle, however, projecting beyond the front end of the shaft and being provided with a notched or serrated feed-wheel, f. The tendency of the spindle e is to remain in line with 8c the axis of the shaft E; but said spindle possesses sufficient elasticity to permit a slight vertical movement of the feed-wheel f when pressure is exerted upon the latter, (see dotted lines f', Fig. 1,) the central opening of the 8: shaft E being flared toward the front end in order to permit this movement of the feed-wheel and spindle.

The degree of elasticity of the spindle may be regulated by means of set-screws adapted 9c to threaded openings in the shaft E and serving to confine the spindle e to said shaft at a point more or less remote from the front end of the same; for the greater the distance between the end of the spindle and the point of 9: confinement of the same the greater will be the elasticity of the spindle, the elasticity decreasing as the distance decreases.

An arm on the frame B carries a transverse pin, l, to which is hung a lever, m, the short 1c

arm of which is provided with an anti-friction roller bearing upon the front end of a spring, *k*, having its fulcrum on a stud on the frame *B* and acted upon at the rear end by a thumb-nut, the adjustment of which regulates the tension of the spring. The tendency of this spring is to retain the lever *m* in either of its extreme positions—that is to say, in the depressed position shown in Fig. 1, or in the elevated position shown in Fig. 2.

To a suitable bearing in the lever *m* is adapted a stem, *n*, carrying at the lower end a beveled disk, *h*, the upper end of the stem being adapted to an opening in a threaded stem, *n'*, by adjusting which the position of the disk *h*, in respect to the lever, may be varied, as desired.

The rear end of the shaft *D* is provided with an operating-crank, *C*, and the two shafts, *D* and *E*, are suitably geared together, so as to turn in opposite directions.

The operation of the machine is as follows: The lever *m* being elevated, as shown in Fig. 2, pressure is applied to the treadle connected to the rod *R*, so as to depress the box *H* and the outer end of the lower shaft, *D*. A shoe-sole, previously prepared by the channeling-machine, so as to present a grooved edge, *r*, and an inclined slot, *u*, adjacent thereto, as shown in Fig. 3, is then adjusted to its proper position in respect to the flange *g* of the shaft *E*, and the shaft *D* allowed to ascend, so as to bend the edge of the sole and press the same firmly against the flange *g* and feed-wheel *f*. The lever *m* is depressed, so that the edge of its disk *h* enters the slot *u*, and the crank *C* is rotated, thereby rotating the shafts *D* and *E* in opposite directions, and causing the sole to be fed through the machine by the action of the feed-wheel *f* thereon, the edge of the sole being bent, as shown, and the disk *h* remaining in the slot *u* and serving to effect the opening of the same, in the manner illustrated in Fig. 4. The feed-wheel *f* is at liberty to yield vertically to accommodate itself to inequalities in the thickness of the sole, without affecting the position of the edge-turning flange *g* on the shaft *E*, the latter always preserving one position and thereby insuring the uniform turning or bending of the edge of the sole, independent of the variations in the thickness of the same.

It should be understood that the edge-bending wheels and the feed-wheel must be so proportioned in respect to each other or so driven as to travel at the same surface speed, otherwise there will be a drag on the work.

In carrying out my invention it is not absolutely necessary that the construction shown

should be adhered to in all cases. For instance, instead of securing the rear end of the spindle *e* to the shaft *E* and relying upon the inherent elasticity of said spindle to hold the feed-wheel *f* to its work, the spindle might be connected to the shaft by a universal joint, the outer end of the spindle in this case being acted upon by a suitable spring, and a kind of spring different from that shown may be used for acting upon the lever *m* or upon an arm which may take the place of said lever, or a fixed slot-opening, blade, or wheel may take the place of the swinging disk *h*. The arrangements shown in the drawings are preferred, however, as they are simple and compact, and have been found to be effective in practice.

I claim as my invention—

1. In a sole-edge-bending machine, the combination of edge bending and feeding wheels and means of rotating the same with a device for opening the thread-slot of the sole simultaneously with the bending of the edge of the latter, as set forth. 75

2. In a sole-edge-bending machine, the combination of edge bending and feeding wheels and means for rotating the same with a thread-slot opener, and means for applying the same to and removing it from said slot, as specified. 80

3. The combination of the shaft *D* and the hollow shaft *E*, each provided with an edge-bending wheel, means for rotating said shafts, and a spindle, *e*, adapted to the hollow shaft *E* and connected thereto at the rear end, but 90 having its front end unconfined and provided with a feeding-wheel, *f*, as set forth.

4. The combination of the shaft *D* with a sole-edge-bending wheel comprising a ring, *j*, and block *i*, detachable from each other and 95 from the shaft *D*, as set forth.

5. The combination of the frame *B*, the sole-edge bending and feeding wheels, and means for rotating the same, the lever *m*, hung to the frame *B* and carrying the disk *h* for opening the thread-slot, and the spring *k* for acting on said lever *m*, as set forth. 100

6. The combination of the sole-edge bending and feeding wheels and means for rotating the same with the lever *m*, the disk *h*, having a 105 stem, *n*, adapted to said lever, and the threaded stem *n'*, for adjusting said stem *n*, as set forth.

In testimony whereof I have signed my name to this specification in the presence of two subscribing witnesses.

CYPRIEN CHABOT.
